HEAT TRANSFERRING MEANS SUITABLE
FOR THERMIonic DISCHARGE
APPARATUSArthur James Young, Danbury, England, assignor
to Radio Corporation of America, a corporation
of Delaware

Application January 22, 1943, Serial No. 473,172

8 Claims. (Cl. 250—27.5)

1

The present invention relates to heat transferring apparatus wherein it is required to effect transference of heat between a stream of fluid and a metallic body.

An object of the invention is to provide a simple and efficient cooling means for an electron discharge device.

Though the invention is not strictly limited to the transference of heat from a cylindrical anode of a tube to a cooling fluid such as air, it will be described in connection therewith. The body may, of course, be any other electrode than that of an anode and its shape may be other than cylindrical, for example it may be of square cross section. The invention is, however, to be considered as applied to heat transferring arrangements in which fins are disposed co-axially about and in heat exchanging contact with the body and in which the fins are mutually spaced apart.

According to the invention, a heat transferring device for effecting transference of heat between a stream of fluid and a metallic body, of the kind in which fins are disposed co-axially about and in heat exchanging contact with the body, the fins being mutually spaced apart, and in which the body and its fins are accommodated in a duct of larger diameter (or of larger cross sectional area) than the outside diameter (or cross sectional area) of the fins and through which duct the stream of fluid flows, is characterized in that there is provided between the wall of the duct and the outer edges of all of the fins at least one continuous barrier whereby fluid entering the duct at one end thereof on one side of the barrier (or if there are more than one barriers on one side of all the barriers), is constrained to pass between the fins in order to reach the other side of the barrier (or barriers) and so to reach the outlet at the other end of the duct.

According to a feature of the invention, a cooling device for the (substantially cylindrical) anode of an electronic device, or vacuum tube, in which fins are disposed coaxially about and in heat exchanging contact with the anode, the fins being mutually spaced apart, and in which the anode and its fins are accommodated in a duct of larger diameter than the outside diameter of the fins and through which cooling fluid (such as air) flows is characterized in that there is provided between the wall of the duct and the outer edges of all the fins at least one continuous barrier whereby fluid entering the duct at one end thereof on one side of the barrier (or

2

if there are more than one barriers on one side of all the barriers) is constrained to pass between the fins in order to reach the other side of the barrier (or barriers) and so to reach the outlet at the other end of the duct.

When a single barrier is used it may take the form of an elliptical annulus extending from the top to the bottom disc. With this form the fluid inlet passages at the successive discs will vary in size and in certain cases this might lead to undesirable unequal cooling of the body or anode, throughout its length. Where such is the case two or more baffles may be used and equal inlet and outlet fluid passages can thus be obtained when necessary.

The coaxial cooling fins may consist of a number of metal discs having a central aperture in which the metallic body, or anode of the tube, fits tightly so that it may be soldered thereto with the minimum amount of solder. The discs are spaced apart by distance pieces in the form of washers, which may be circular, fitting the body or anode.

In place of using a series of discs to form a built up unit the device may be made by milling slots in a solid body or cylinder of brass or other suitable good conducting metal.

The applicant has, in connection with the cooling of the anodes of the thermionic devices, with which he is principally concerned, commonly used axial air flow radiators with both coaxial and radial cooling fins. For high specific loadings, the coaxial cooling fins (i. e. those in which the stream of cooling fluid moves radially inwards or outwards and the radiator is in form similar to a standard series of washers) have the advantage that the velocity of the fluid can be maintained more nearly constant over the radial length of radiator, and further the inlet and outlet orifices of the radiator itself can usually be of such dimensions that the speed of flow of the fluid will be suitable to the case in which a small radiator is required. Where the primary requirement is small size then high speed of flow of the fluid (about 30 to 40 metres/second) will be required while where silence is the primary consideration a low speed of flow (about 15 metres/second) will be required. In the latter case, axial flow with a radial fin is preferable.

Difficulties with devices providing radial flow (to which devices the present invention is directed) have been that the addition of suitable means for admitting and exhausting the air have led to large increases in the diameter of the

radiator and its holder. Many of the advantages of devices providing radial flow have therefore been lost.

The present invention provides, therefore, a method of mounting a radial flow radiator in an air duct so that the overall diameter is very little greater than that of the radiator itself, for instance an overall diameter (that is over the baffle) of 90 mm., and a diameter for the radiator of 80 mm. have been found suitable for an air-cooled tube.

The invention is illustrated in the accompanying drawing in which:

Fig. 1 is an elevational view, partly in section, showing cooling fins provided with a single barrier; and

Fig. 2 is a fragmentary perspective view of cooling fins provided with a double barrier.

A particular embodiment of the invention, in its application to an air-cooled tube, is illustrated in Fig. 1 of the accompanying drawing. In this embodiment the metallic anode A, which forms part of the envelope of the tube, is provided with tubular member A1, circular, washer-like radiator fins F, spaced apart from each other and in close heat exchanging relationship with the anode. Fitted about the edges of all the washers is a continuous barrier B, which, as illustrated, consists of an elliptical annulus extending from the lower edge of the uppermost washer W1, past the edges of all the succeeding washers, to the upper edge (not visible in the figure) of the lowermost washer W2. The upper end of the annulus is in contact with the uppermost washer at one end of a diameter of it and of the duct, and the lower end of the annulus is in contact with the lowermost washer at the other end of the same diameter of the duct. Thus the duct is divided into two parts, between which the only communication for the cooling fluid is by way of the spaces separating the several washers from each other. The assembly of tube and fins may be held, by means of a clamp, in a cylindrical fluid airduct K of larger internal diameter than the diameter of the washers, so that a space exists between the wall of the duct and the washers. The barrier is fitted between the wall of this duct and the edges of the fins.

Suitably in such a heat transferring device applied to such a tube, wherein the overall diameter of the fins is 80 m. m., in which there are thirteen washers of brass 1.5 m. m. thick, having a root diameter of 42 m. m. and spaced apart 1.5 m. m., and in which the overall diameter of the duct is 90 m. m., the dissipation of heat may be equivalent to 400 W for a current of air at a temperature, at the inlet, of 30° C. flowing at the rate of 25 cubic feet/minute (equivalent to a speed of approximately 17 metres/second), or to 800 W for a current of air at the same temperature flowing at the rate of 50 cubic feet/minute (equivalent to a speed of approximately 35 metres/second). The maximum temperature attained is 150° C.

If copper were used for the washers, the heat transferring device could be made smaller, but usually it is not desired to make it smaller since the noise due to the higher speed of the air might be objectionable.

It will be appreciated that with a barrier as above described, the effective inlet and outlet orifices at the top and bottom of the device are widely different from each other. By means of a modification illustrated by Figure 2 of the ac-

companying drawing, in which two members B', or curved barriers are employed, a further improvement may be made by which these differences between the effective inlet and outlet orifices which in certain circumstances may be disadvantageous, may be reduced. In this arrangement, the two barriers may be so constructed as, together, to constitute a continuous member bent so as to extend from an edge of the uppermost fin at one end d' of a diameter thereof to a point d'' on the edge of the lowermost fin, back to the edge of the uppermost fin at the opposite end of said diameter, down again to a point on the edge of the lowermost fin, and thence to the uppermost fin to join the uppermost fin at the same one end d' of the diameter, the two points d'' on the lowermost fin being at the two ends of a diameter thereof displaced by 90° from the first mentioned diameter. The shape of the barrier about the bends at d' and d'' will determine whether there is any difference between size of inlet and outlet. In the limiting case, if the shape of the barrier at the "bends" were rectangular, the cross section could be made exactly equal, but in practice the corners might become almost "dead" owing to eddies, and therefore the most suitable shape would be found by experiment.

The barrier, or barriers, as the case may be, may be attached either to the inner wall of the duct L, or to the outer edges of all or some of the washers.

Although, in the specific description, washers have been referred to, in which case the several washers would be separated by spacing or distance rings, or washers of smaller diameter than those constituting the fins, the radiator may be produced from a solid cylinder of brass, or other suitable metal, in which circular co-axial slots have been cut. In either case, the anode should preferably be a close fit in the central orifice of the radiator so that it may be soldered to the inner wall of the orifice with a minimum of solder and a minimum risk of having air pockets or gaps between the anode and radiator.

It is not necessary that the tube and its radiator be fixed in the duct L, it may merely be slipped therein.

What I claim is:

1. A heat transferring device for effecting transference of heat between a stream of fluid and a cylindrical metallic body, of the kind in which a plurality of circular cooling fins are disposed coaxially about and in heat exchanging contact with the body, the fins being mutually spaced apart, and in which the body and its fins are accommodated in a cylindrical duct of larger diameter and cross sectional area than the outside diameter and cross sectional area of the fins and through which duct the stream of fluid flows, characterized in that there is provided between the wall of the duct and secured to different positions on the outer edges of all of the circular cooling fins at least one continuous barrier whereby fluid entering the duct at one end thereof on one side of the barrier is constrained to pass between the fins in order to reach the other side of said barrier and so to reach the outlet at the other end of said duct.

2. A cooling device for the anode of an electron discharge device in which circular cooling fins are disposed coaxially about and in heat exchanging contact with the anode, the circular cooling fins being mutually spaced apart, and in which the anode and its cooling fins are con-

centrically located in a cylindrical duct of larger diameter than the outside diameter of the fins and through which cooling fluid flows, characterized in that there is provided between the wall of the duct and the outer edges of all the fins at least one continuous barrier whereby fluid entering the duct at one end thereof on one side of said barrier is constrained to pass between the fins in order to reach the other side of the barrier and so to reach an outlet at the other end of the duct.

3. A device as claimed in claim 1, wherein a single barrier is used which is in the form of an elliptical annulus extending from the topmost to the bottommost of said fins.

4. A device as claimed in claim 2 wherein a plurality of baffles are used so that equal inlet and outlet fluid passages can be obtained.

5. A heat transferring device for an air-cooled vacuum tube having an anode, said device having a plurality of coaxially spaced metallic fins surrounding said anode, comprising a fluid duct surrounding said fins, and two barriers which are so constructed as, together, to constitute a continuous member bent so as to extend from an edge of the uppermost fin at one end of a diameter thereof to a point on the edge of the lowermost fin, back to the edge of the uppermost fin at the opposite end of said diameter, down again to a point on the edge of the lowermost

30

fin, and thence to the uppermost fin to join the uppermost fin at the said one end of the diameter, the two points on the lowermost fin being at the two ends of a diameter thereof displaced by 90° from the first mentioned diameter.

5 6. A device as claimed in the preceding claim wherein the barriers are attached to the inner wall of the duct.

10 7. A cooling device for an electron discharge device having at least a cathode and an anode, comprising a plurality of mutually spaced circular metallic fins coaxially arranged to surround the anode of said electron discharge device, a cylindrical duct surrounding said circular fins and a continuous barrier surrounding and attached to a different position on each one of said fins, and so arranged as to divert the flow of a cooling fluid for said anode along different portions of said fins.

15 8. A cooling device for an electron discharge device having at least a cathode and an anode, comprising a plurality of mutually spaced circular metallic fins coaxially arranged to surround the anode of said electron discharge device, a cylindrical duct surrounding said circular fins and an elliptical barrier surrounding said fins and arranged to divert the flow of a cooling fluid along different portions of said fins.
